UNITED STATES PATENT OFFICE

2,292,602

PRINTING DEVICE

Joseph P. Biondi, Los Angeles, Calif.

Application April 16, 1940, Serial No. 329,893

2 Claims. (Cl. 101—116)

This invention relates to means for printing or stamping designs directly upon flat and curved articles such as chinaware, crockery, bathroom fixtures, stoves, wall panels and paper, bottles, etc. The article to which the design is to be transferred may be of any known material such as glass, leather, tile, metal or the like. Various tones and tints of color may be reproduced and if desired, the colors may be made permanent by any of the well known processes.

The process known as decalcomania is utilized in this invention for transferring designs from one medium to another. The process itself is old and well known and generally consists of transferring a certain design from paper to any surface suitable for receiving it, but in this invention, the design to be transferred may be on other materials than paper and made in the form of a cylinder instead of the common practice of making the transfer from a flat surface material. In making the transfer in accordance with this invention, an especially constructed cylinder is presented having novel means associated therewith which effectively carries on the transfer in a continuous manner so as to produce repeated designs in a logical order. In addition, means are provided to avoid wear on the prime holder of the design by introducing an intermediary element between the prime holder and the pressure element.

One of the principal objects of this invention is to present a device which is operative to make continuous prints, by decalcomania processes, from a cylindrical prime holder of the design to any surface suitable to receive the design.

Another of the objects is to provide a design transferring device which is capable of giving perfect results in a rapid and economical manner.

Still another object is to provide means for transferring designs in which the working pressure upon the prime design holder is uniform and at a predetermined pressure adjustment.

Other objects, advantages and features of my invention will appear from the accompanying drawings, the subjoined detailed description, the preamble of these specifications and the appended claims.

Applicant is about to illustrate and describe one of the forms of his invention in order to teach one how to make, use and vend the same, but it is to be understood that the drawings and description thereof are not to limit the invention in any sense whatsoever, except as limited by the appended claims.

In the drawings:

Fig. 1 shows the preferred form of the invention in side elevation, parts being broken away to show in sections.

Fig. 2 shows a part of Fig. 1 in enlarged sectional view.

Fig. 3 is an end elevational view.

Fig. 4 is an elevational view, partly in section of a portion of the invention.

Fig. 5 is a horizontal view taken substantially along the line 5—5 of Fig. 4.

Fig. 6 is a view taken substantially along the line 6—6 of Fig. 1.

Fig. 7 is a side elevational view of a portion 15 of the invention, with parts broken away to show sections thereof.

Fig. 8 is a side elevation of a slightly modified form of the invention, showing parts in section.

Fig. 9 is a sectional view at right angles to 20 Fig. 8.

Fig. 10 is a cross sectional view of a slightly modified form of the invention.

Fig. 11 is a plan view of another modified form of the invention.

Fig. 12 is a view taken along the line 12—12 of Fig. 11.

The preferred form of the invention comprises end frames 1 and 2 to rotary support the superposed cylinders 3 and 4. Each end frame includes lateral uprights 5 and 6 having diverging legs 7 and 8 of angle iron and feet 9 and 10 respectively which may be fixed to the floor by bolts or screws.

At the upper part of the frame, each upright 33 is provided with offset portions 11 and brackets 12 to support flat shelves 13 as shown. At the very top of each frame is a slit clamp 14 to hold the ends of the axle 15 of the cylinder 3. This clamp has a lower section 16 which is integral 40 with or bolted to the top of the frame, and a removable top section 17. The top section is held to the lower section by the quick acting release hand bolts 18 which have their lower ends pivoted to the lower section at 19. The sides of the sections are slotted at 20 so that when the handles of the bolts are loosened, the bolts can be swung away from the top section leaving it free to be removed and hence the axle 15, cylinder 3 and associated parts.

The lower roller or cylinder 4 and its axle ends 21 are supported by the end frames in the adjustable bearing blocks 22. Lateral ribs 23 on each side of the block provide a groove so that the block can be moved vertically therein. A cross web 24 of each frame is provided with

integral boss 25; the boss having a threaded bore in which is the threaded stem 26 of the bearing block adjuster. One end of the stem has a hand wheel 27 fixed thereto and the other end has free action in the bored boss 28 which is integral with the block 22. The lock nut 29 is provided to hold the stem in adjusted position. The roller 4 has extended spacer hubs 30 and 31 to keep the roller in position. This roller is an idler and is rotated by friction with the cylinder or upper roller 3.

The top cylinder 3 has the spider ends 32 and 33 each of which have central hub sleeve 34 and rim 35 joined together by the cross bar 36. The rim has a protruding lip 37 forming an annular recess into which snugly fits an annular removable ring 38, configurated as shown, held together by a plurality of spaced apart bolts 39 which have threaded engagement with the rim.

To form the cylinder intermediate the ends 32 and 33 are inner fabric or mesh cloth 40 and outer fabric or mesh cloth 41. The cylinder ends are held spaced apart by the rigid bar 42, its arms 43 and 44 and their respective integral sleeves 45, as well as the washers 46. The sleeves 45 are fixed to the axle 15 by any suitable means, such, for instance, by a key or set screw in any well known manner. Since the axle 15 does not rotate, the arms 43 and 44 remain stationary. A squeegee or the like 47, of soft rubber or other suitable resilient material, is cemented, vulcanized or otherwise held in the slot 48 of the bar 42, the slot and squeegee extending substantially the full length of the cylinder.

By referring to Fig. 4 of the drawings, it will be seen that the bar 42 has an integral plate 49 which is arranged to slide vertically in the space 50 between the legs 51 and 52 of the arms 43 and 44. The legs are turned to form flanges 53, the ends of which snugly engage the sides of the bar 42. Over the plate 49 is a compression coil spring 54, shown pressed beneath a square plate 55. This plate is vertically adjustable by the set screw 56 which has a long threaded stem in threaded engagement with a threaded bore in the web 57, as shown. The head of the screw is preferably squared so that the screw can be easily raised or lowered by using the proper wrench.

To hold the bar 42 and its plate 49 in proper alignment with the arms 43 and 44, the plate 49 near its ends is provided with integral and vertical beads 58 which slide in vertical grooves 59 on the inner sides of the arms, see Fig. 5. By this arrangement, the bottom edge of the squeegee 47 is held firmly, but resiliently against the inner surface of the fabric 40. The pressure is just great enough to transfer the design on the outer surface of the fabric 41 to the thing passed between the rollers 3 and 4. The fabrics 40 and 41 should be seamless when it is desired to print continuous lines or designs without any noticeable break in its continuity. These fabrics may be silk, but the one having the most wear may be double or even made of stronger material such as metal or any tough synthetic material such as "Nylon." The outer fabric 41 may be doubled or even tripled when it is desired to slow down the feed of the ink, color or dye therethrough. Wherever practical, a single screen or fabric may be used instead of the two as shown. Gold colors can be printed by applicant's device just as easy as any other colors which are generally more viscous than gold paint.

When sheets of paper and similar flexing mate-

rials are printed upon, the outer surface of the roller 4 is preferably hard, such as steel, hardened plastics and the like, but when fragile material such as glass plates, sheets of ceramic materials, etc. are printed upon, the roller 4 is preferably surfaced with a soft substance such as sponge rubber.

To rotate the upper cylinder or roller 3, each end hub thereof is fixed to a bearing sleeve by keying means or the set screw means 60. On one end of the roller is shown a bearing sleeve 61 and a similar one 62 on the other end. Each sleeve is free to rotate upon the fixed axle 15 and each is keyed to a bevel end gear 63. At the sides of the device are inclined shafts 64 and 65 journalled in bearing boxes 66 at their ends, the boxes being rigidly held to their respective adjacent standards. Keyed to the ends of shafts 64 and 65 are bevelled gears 67, the top ones of each shaft meshing with their adjacent gears 63 and the bottom ones meshing with bevelled gears 68 which are keyed to horizontal shafts 69 and 70.

The shafts 69 and 70 have end couplings 71 and 72 which are joined together by the short shaft 73. This short shaft is keyed to a worm wheel 74 which is meshed with the worm 75 fixed to the shaft of the electric motor 76. A cross beam 77 has its ends fixed to the end frames 1 and 2, and supports the motor 76. A variable speed motor is used in conjunction with the reduction gearing shown so that the rollers will turn very slowly.

The modified form of the invention shown in Figs. 11 and 12 employs only the print carrying cylinder or roll 80 which has end rings 81 to receive and hold the double fabrics 82 and 83. The fabric 82 receives the print to be transposed upon the article to be printed, and the fabric 83 receives the wear from the squeegee 84. Both fabrics are held to the recess 85 of the ring by the collar 86. The ring 81 has a cross bar 87 and a hub 88 which is fixed to a bearing sleeve 89 which rotates upon an axle 90. At each end of the axle 90 is a port 91 to which the axle 90 is securely fixed by any suitable manner such as by keying or by set screw; the elements 90 and 91 may be welded if desirable. To support the elements 91 at both ends of the cylinder 80, is a U-shaped bar 92 having the handle 93. The squeegee 84 has the usual top plate 94 which is held to the end arms 95. The end arms are fixed to the axle 90 by sleeves 96. The construction of the cylinder 80 is exactly the same as the construction of the cylinder 3 of the preferred form of the invention and will not, therefore, be further described in detail. The principal difference between the preferred form and the modified form, is that the preferred form is operated by electric motor and various gearing to reduce the speed whereas the modified form is operated by hand. The preferred form, or the manual operative one, is very useful for printing designs upon jars, vases, etc. which could not ordinarily be printed in the preferred form of the invention.

Any one of the inventive forms receive their supply of ink, paint, dye, or other kind of coloring material, by manual means into the open cylinder upon which is cemented, glued or otherwise fixed the design stencil or pattern. Since the ends of the cylinder are open, except for the cross bar 36 of the preferred form; f. i., the ink or coloring material may be poured directly into the cylinder, or in the event the ink is too thick for pouring, it may be put into the cylinder and

spread across same with a flat stick that will not injure the fabric.

In order to feed ink to the cylinder 3 of the preferred form of the invention while it is in motion, the axle 15 is provided with a small bore 100 extending from the end 15' to one or more ports 101 along the axle within the cylinder. Fixed to the axle end 15' is a hand pump 102 which may be any type of grease gun or the like now commonly used for forcing lubricant into the bearings of automobiles. Such a gun for use with this invention may have a cylinder 103 open at both ends. One end has a threaded portion 104 upon which is threaded a removable cap 105. The other end of the cylinder has a resilient band clamp 106 fixed thereto which can be tightened around the end of the axle 15 by turning the screw 107 in an obvious manner. Within the cylinder is a piston 108 fixed to a rod 109 which terminates into a cross hand grip element 110. To load ink into the pump, it is merely necessary to remove the cap 105 and the piston 108. When these parts are re-assembled with a load of ink in the cylinder, the ink can be fed as required into the large cylinder 3 while it removes by turning the element 110. Obviously, such a pump may be used upon any of the other forms of the invention should there be some advantage in doing so.

The form of the invention shown in Fig. 10 has all the parts and elements of the preferred form of the invention except that a single screen or fabric 111 is employed instead of the double ones 49 and 41 as clearly shown in Fig. 2. The number of fabrics to be used will depend upon the viscosity of the ink used, the perforation degree of the design stencil etc. Whenever necessary, the fabric is starched or otherwise made stiff or hardened to proper cylindrical form so as to facilitate its placement upon the cylinder ends and also to prevent collapse of the cylinder while under special use and conditions.

Figs. 8 and 9 show rollers 3 and 4 and a charge of coloring matter (ink) within the cylinder 3. The element 113 is a fragile piece of ceramic ma-

terial being printed with the design upon the flat stencil 114. In this manner of using the preferred form of the invention, the stencil is not cylindrical or curved to fit the roller 3; instead, the stencil is fed between the rollers 3 and 4 along with the thing to be printed. Since a fragile plate is being fed between the rollers, the roller 4 is provided with an outer resilient padding such as sponge rubber to avoid breakage of the plate.

Since the paint or coloring matter when cold is apt to become stiff and too thick for readily working its way through the interstices of the screens and fabrics upon the printing roll, means are provided for heating the paint and keeping it at the proper consistency. This may be done by circulating a heating fluid, such as steam, hot water or hot oil, through bores in the axle or by providing an electric or gas heating unit in the lower cylinder 4.

Having thus described my invention, what is claimed as new and desired to be secured by Letters Patent is:

1. In a device for printing designs comprising a roller and a cylinder having their curved surfaces substantially in abutment, a frame for supporting the roller and cylinder, said cylinder having its curved walls formed of resilient reticulated material adapted to pass ink, said cylinder having rigid ends with an annular recessed portion adapted to receive the ends of the said material, an annular ring-like member adapted to enter the recess and firmly hold the ends of the material therein, an axle fixed to the frame and extending through the cylinder and rigidly supporting an elongated squeegee therein, means including a sleeve connected to the said cylinder, and a motor, for driving the said cylinder, connected to the sleeve.

2. The device recited in claim 1 wherein rotary shaft means are provided at each end of the cylinder for driving sleeves attached to each end of the cylinder.

JOSEPH P. BIONDI.
